UPHOLSTERY CONSTRUCTION

Albert M. Bank, Jersey City, N. J., assignor to
Sylvia Bank, Jersey City, N. J.

Application April 3, 1940, Serial No. 327,599

6 Claims. (Cl. 155—179)

This invention relates to upholstery construction. It is particularly directed to a spring seat in which foundation springs are mounted on webbing fixed to a seat frame, and the like articles.

An object of this invention is to provide upholstery construction of the character described comprising a frame provided with webbing for supporting the foundation springs, and improved means to aid in supporting the webbing, provided with a take-up to permit regulation of the webbing.

A further object of this invention is to provide a neat, strong and durable upholstery construction of the character described, which shall be relatively inexpensive to manufacture, easy to adjust, and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown various possible illustrative embodiments of this invention,

Fig. 1 is a top plan view of a spring cushion seat forming part of upholstery construction, embodying the invention;

Fig. 2 is an enlarged cross-sectional view taken on line 2—2 of Fig. 1;

Fig. 3 is a bottom plan view of the structure shown in Fig. 1;

Fig. 4 is an enlarged cross-sectional view taken on line 4—4 of Fig. 1;

Fig. 5 is a cross-sectional view taken on line 5—5 of Fig. 3;

Fig. 6 is a cross-sectional view taken on line 6—6 of Fig. 5;

Fig. 7 is an enlarged cross-sectional view taken on line 7—7 of Fig. 1;

Fig. 8 is a bottom plan view of upholstery construction embodying the invention, and illustrating a modified form thereof;

Fig. 9 is a bottom plan view of upholstery construction embodying the invention, and illustrating a further modified construction;

Fig. 10 is a bottom plan view of a sofa provided with an upholstery support embodying the invention, and illustrating a still further modified construction; and

Fig. 11 is a cross-sectional view taken on line 11—11 of Fig. 10.

Referring now in detail to the drawings, 10 designates upholstery construction embodying the invention, here shown in the form of a spring cushion seat for an upholstery chair, or the like article. The same comprises a wooden seat frame 12 having rear and front walls 13 and 14, and side walls 15 and 16.

Attached to the underside of front and side walls 14, 15 and 16 of the frame 12, by nails 22 or in any other suitable manner, is a one piece webbing 17 made of burlap or the like material. The rear edge of webbing 17 is folded back to form a sleeve 18 disposed parallel to and spaced from the rear wall 13. The folded back portion 15 of the webbing is stitched to the body of the webbing by a line of stitching 19.

The front end of the webbing 17 is folded under about a rear folded line 20 and then folded rearwardly again about a folded line 21 to produce 20 a portion of triple thickness.

Within the sleeve 18 is a longitudinal wire rod 76. Attached to the lower end of rear wall 13 are a plurality of spaced, angle shaped brackets 27. Interconnecting the brackets 27 with the 25 rod 76 are a plurality of parallel coil tension springs 28 disposed in the plane of webbing 17 to tension the latter. The usual foundation springs 30 are mounted on the webbing 17.

Means is provided to aid in supporting the 30 webbing 17, and to prevent sagging thereof. To this end, there is attached to the inner side of rear wall 13, at the middle thereof, a channel shaped bracket 40 having a vertical portion 41 contacting the inner surface of rear wall 13, and 35 parallel portions 42 and 43 extending from the upper and lower ends of portion 41 and contacting the top and bottom edges of said rear wall. Said portions 42 and 43 are formed with openings to receive nails or other fastening members for attaching bracket 40 to said front wall.

Portion 41 of bracket 40 is provided with a pair of spaced, humped or offset portions 44 and 45. The lower offset portion 45 is formed with an opening 48. Hinged to the upper offset portion 45 46 is a plate 50 having a slot 51 adjacent its upper end through which said offset portion 46 passes. The plate 50 is formed with a pair of notches 52 at the opposite side edges thereof, for the purpose hereinafter appearing. Said plate 50 is furthermore formed with a central opening 55 adjacent its lower edge.

Extending through the opening 48 in the offset portion 45 is the shank 56 of a take-up screw 57. Said screw 57 has a head 59 disposed within said 55 offset portion. Said shank 56 passes through the

opening 55 in the plate 50. Screwed to the outer end of said shank is a wing nut 60. A washer 61 may be interposed between the nut and the plate 50. The purpose of the plate and take-up screw 57 will be described hereinafter.

Attached to the upper edge of front wall 14 are a pair of spaced metal straps 62, symmetrically disposed with respect to the middle of the frame. Each strap 62 may be attached to the front wall 14 by a nail 63 passing through an opening in said strap. Disposed beneath the webbing is a web supporting member 70 preferably made of a single piece of wire. The same comprises a pair of crossing inclined arms 71 interconnected at their front ends by an interconnecting portion 72. The arms 71 are disposed beneath the webbing 17 and engage within the notches 52 of plate, the interconnecting portion 72 contacting the rear surface of said plate.

The arms 71 are formed at their rear ends, with upwardly extending humped or offset portions 75 passing through registering openings or slots in the triple thickness portion of the webbing 17. Interconnecting the offset portions 75 with the straps 62 are coil tension springs 76a. Washers 77 may be received on the humped portions 75 contacting the top surface of the webbing.

It will now be understood that the wire member 70 interconnects the strap 62 with the plate 50 through springs 76a, and hence aids in supporting the webbing. Member 70 keeps the plate 50 in contact with the washer 61 which presses against the nut 60. Upon turning the wing nut 60, the plate 50 is pivoted about its upper hinged end in a counter-clockwise direction, looking at Fig. 5 of the drawings, to exert a pull on member 70 to the right, to further tension springs 76a.

In Fig. 8 there is shown upholstery construction 10a embodying the invention, similar to the construction 10, with the exception that two auxiliary supports 80 are provided for the webbing 17, each similar to the webbing support shown in Figs. 1 to 7 of the drawings, with the further exception however that the arms 81 of said units are curved instead of being substantially straight, as are arms 71 of member 70. The arms 81 may be produced by first bending the arms outwardly at points somewhat spaced from the portion 82 which interconnects said arms. The outer ends of the outwardly bent arms are then flexed inwardly and pushed through the openings in the webbing 17 for engagement with the springs 76a. The inward flexing of the arms curves the arms to give some take-up during flexing of the webbing, so as to prevent ripping of the openings in the webbing through which the humped portions 75 pass.

In Fig. 9 there is shown upholstery construction 10b, similar to the construction 10, with the exception that the arms 85 of the auxiliary webbing support 86 are not crossed but diverge outwardly, and are sinuous in shape, and are attached at the outer ends thereof, as at 87, directly to the underside of the front frame wall 14.

In Figs. 10 and 11 the auxiliary supports for the webbing 17 of a sofa or other upholstered chair, comprise a plurality of units 90, each consisting of an elongated metal bar 91 connected by wire loop 92 to the pivot plate 50, similar to the plate 50 of Figs. 1 to 7, and provided with take-up means, as shown in said figures. The bar 91 has a turned over sleeve 94 at one end to receive one end of the loop 92. At the other end of bar 91 is a slot 96 through which an anchor member 97 is

passed, said anchor passing through an opening in the webbing 17 and being connected by a coil tension spring 98 to the front wall 14 of the frame. As shown in Figs. 5 and 7, a strip of lining material 17a may be attached at one edge to the rear end of the webbing 17, and at its other edge to the upper edge of rear wall 13 to cover the space between the webbing and the rear wall and to overlie the springs 28.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. In upholstery construction, a frame, webbing attached to the underside of the frame, a member hinged to a wall of said frame, screw threaded means for swinging said hinged member about its pivotal point, a member contacting the underside of the webbing and having crossing arms, and an interconnecting portion engaging said hinged member, and spring means to interconnect the free ends of said arms to the upper portion of an opposite wall of said frame.

2. In upholstery construction, a frame, webbing attached to the underside of the frame, a bracket attached to a wall of the frame, and having a portion contacting the inner surface of said wall, and portions contacting the upper and lower edges of said wall, the portion which contacts the inner surface of the wall being formed with upper and lower offsets, a plate having a slot through which the upper offset passes, the lower offset being formed with an opening, a screw having a shank passing through the opening in the lower offset, said screw having a head within said offset, said plate being formed with an opening adjacent its lower edge through which the shank of the screw passes, a nut on said shank, said plate being formed with a pair of notches at the opposite edges thereof, a member

made of a single piece of wire having arms, and a portion interconnecting adjacent ends of said arms, and contacting the inner surface of said plate, portions of said arms passing through said notches, said arms contacting the underside of said webbing, and being formed with upwardly offset portions extending through openings in said webbing, and spring means to interconnect the offset portions on said arms with an opposite wall of said frame.

3. In upholstery construction, a frame, webbing attached to the underside of the frame, a member hinged to a wall of said frame, screw threaded means for swinging said hinged member about its pivotal point, a member contacting the underside of the webbing and having crossing arms, and an interconnecting portion engaging said hinged member, and spring means to interconnect the free ends of said arms to the upper portion of an opposite wall of said frame, said arms being curved.

4. In upholstery construction, a frame, webbing attached to the underside of the frame, a member hinged to a wall of the frame, means for swinging said hinged member about its pivotal point, a member contacting the underside

of the webbing and comprising a pair of arms, and a portion interconnecting said arms, the interconnecting portion of said member engaging said hinged member, and spring means to interconnect the free ends of said arms to the upper portion of an opposite wall of said frame.

5. In upholstery construction, a frame, a bracket fixed to a wall of said frame and being formed with a pair of offset portions, a plate having a slot receiving the upper offset portion and being formed with an opening adjacent its lower edge, the lower offset portion being formed with an opening, a screw having a shank passing through said opening in the lower offset portion, and a head within said lower offset portion, said shank passing through the opening in said plate, a nut on said shank, said plate having notches in the side edges thereof, a member made of a single piece of wire having arms interconnected at one end, the interconnecting portion of said member 20

contacting the inner surface of said plate, and portions of said arms passing through said notches, and means to connect said arms to an opposite wall of said frame.

5. In upholstery construction, a frame, webbing attached to the underside of the frame, a member pivoted adjacent its upper end to the inner side of a wall of said frame, means engaging a portion of said member below its pivotal point, for swinging said member toward the wall of said frame, said member having notches on opposite sides thereof, and a member made of a single piece of wire having arms, and a portion interconnecting said arms, said arms passing through said notches, and the interconnecting portion engaging said pivoted member, and means to connect said arms to an opposite wall of the frame, said arms contacting the underside of said webbing.
